UNITED STATES PATENT OFFICE.

WILLIAM H. CONE, OF DETROIT, MICHIGAN, ASSIGNOR TO THE COAL PRODUCTS AND POWER COMPANY, OF DETROIT, MICHIGAN, A CORPORATION OF MICHIGAN.

PROCESS OF MANUFACTURING GAS.

No. 922,857.

Specification of Letters Patent. Patented May 25, 1909.

Application filed July 3, 1908. Serial No. 441,773.

To all whom it may concern:

Be it known that I, WILLIAM H. CONE, a subject of the King of Great Britain and Ireland, residing at Detroit, in the county of Wayne and State of Michigan, have invented certain new and useful Improvements in Processes of Manufacturing Gas, of which the following is a specification, reference being had therein to the accompanying drawings.

The invention relates to the manufacture of gas from bituminous coal or other fuels high in volatile matter, and it is the object of the invention to convert practically all the carbon and hydrocarbon into a permanent and relatively rich gaseous product.

To this end the invention consists in the process as hereinafter set forth.

The drawing illustrates diagrammatically an apparatus suitable for the carrying out of my improved process.

It is generally understood that the distillate formed by the coking of bituminous fuels contains a large percentage of tar and other heavy condensable hydrocarbon vapors which must be eliminated before the gas is in condition for use. This requires a complicated purifying apparatus, while a considerable percentage of the weight of the fuel is thrown out in the form of tar and is not available for the manufacture of gas. With my improved process the distillation of the volatiles from the fuel is carried on under such conditions as to result in the formation of noncondensable gaseous products, and these are commingled with carbon-monoxide gas formed by the combustion and decomposition of the solid carbon in the fuel.

I preferably carry out my process by the use of the apparatus illustrated, in which A A' are two cupolas arranged side by side. Each of these cupolas is provided with a combustion chamber B in its lower portion, and above this chamber a distillation chamber C. Between these chambers is a twyer D and at the upper end of said distillation chamber is a second twyer E. The tuyers D and E of the two cupolas are cross-connected by valve-controlled conduits, and, as shown, F is a conduit connecting the twyer E of the cupola A' with the twyer D of the cupola A. These conduits F F' contain controlling valves G G' by which either one of the conduits may be closed or opened.

Below the combustion chamber B of each

of the cupolas is arranged a twyer H, and these tuyers are alternatively connected with an air blast conduit I and a gas conduit J. Valves K K' are arranged to control these connections.

The lower ends of the cupolas are preferably provided with a water seal L permitting the withdrawal of the ashes from the cupolas and at the upper end of each cupola is a conduit M leading to the stack and controlled by a valve or damper N.

O is a fuel charger for introducing a measured quantity of the fuel into the upper end of each cupola, and P is a normally closed poking aperture.

In carrying out the process, a suitable quantity of the fuel is first ignited in both of the cupolas, and the valves are adjusted so as to connect both cupolas at their upper ends with the stack and the tuyers H at the lower ends with the air blast pipe I. Active combustion is maintained in the cupolas until the fuel therein is brought into a state of incandescence up to the level of the twyer D. The valves are then adjusted first to cut off the stack connection and then to establish communication between the twyer D of one cupola and the twyer E of the adjacent cupola, and, in the adjustment shown, the valve G' is opened to establish communication through the conduit F', while the valve G closes the conduit F. Green fuel is then introduced from the charger O into the distillation chamber C of the cupola A, and the valves K K' are adjusted so as to connect the twyer H of the cupola A with the gas conduit J, and the twyer H of the cupola A' with the air conduit I. With the parts in this position of adjustment, the air entering through the twyer H into the lower end of the cupola A' will pass through the entire body of fuel within this cupola, and will pass through the twyer E and conduit F' to the twyer D of the cupola A, and thence downward through the incandescent fuel to the twyer H, which is in communication with the gas conduit J. During this operation active combustion is first produced in the cupola A', and the products of this combustion, together with a certain amount of water vapor rising from the water seal, will pass through the conduit D' into the cupola A, where the carbon-dioxide is reduced to carbon-monoxide, and the water vapor is decomposed to form carbon-monoxide and hydrogen. At the same time, the heat

of the incandescent fuel in the cupola will be communicated to the green fuel thereabove in the chamber C, and the volatile matter of said fuel will be distilled. Exit for the distillate at the upper end of the distillation chamber is cut off by the closure of the valves N and G. Consequently it is forced downward into the incandescent fuel therebeneath where it is commingled with the carbon-
10 monoxid and hydrogen.

In the passage of the distillate directly into and through the incandescent fuel the heavy and condensable products, such as the tars, will be broken up, a portion of the carbon being freed and united with the coke, while the remaining hydrocarbon will be changed into the form of relatively permanent gases. These will be commingled with the carbon-monoxid, and will greatly enrich
20 the latter.

When the green fuel in the cupola A is completely coked the valves are reversed, opening the conduit F and closing the conduit F', and at the same time coupling the
25 twyer H for the cupola A with the air conduit and the corresponding twyer in the cupola A' with the gas conduit. This will cause the air entering the cupola A to pass through the entire mass of fuel therein, causing active
30 combustion therein, which will restore the heat lost by distillation and decomposition. If necessary, the coked fuel in the distillation chamber may be broken up by poking, and this, as well as the fuel therebeneath, will be
35 brought to a state of incandescence. In the cupola A' a charge of green fuel is introduced into the distillation chamber and this the same process of simultaneous distillation, decomposition of the carbon-dioxid and the
40 cracking up of the heavy hydrocarbons will be carried on in this cupola, resulting in the production of a rich permanent gas.

Considering both cupolas as a unit, it will be observed that active combustion is maintained at one end, decomposition at the other end, and coking and distillation at an intermediate point, the distillate being commingled with the products of the active combustion and passing therewith into the
50 zone of decomposition. The periodic reversal restores the heat lost by decomposition and maintains the heat for distillation substantially constant, while the supply of fuel is renewed in the intermediate zone and the
55 ash is removed at each end. Thus practically all the carbon and hydrocarbons present in the fuel are converted into a permanent and rich gas.

What I claim as my invention is:
60 1. The process of generating gas which consists in blasting through a mass of fuel to maintain the same incandescent and to generate producer gas, in placing green fuel adjacent and in coking proximity to the incandescent fuel but out of the path of the

blast whereby coking is effected, in passing the distillate commingled with the blast gases through a portion of the incandescent fuel, and after coking passing the hot blast gases which have previously passed through the incandescent fuel through the coked fuel also to bring the same to incandescence.
70

2. The process of generating gas which consists in blasting alternately in opposite directions through a body of fuel to maintain the same incandescent and to generate producer gas, in feeding green fuel adjacent and in coking proximity to the incandescent fuel intermediate the blast ends and temporarily out of the blast, in commingling the
75 distillate from said green fuel with the blast gases and passing it therewith through a portion of the incandescent fuel, and after coking passing the hot blast gases which have previously passed through the incandescent fuel through the coked fuel also to bring the same to incandescence.
80

3. The process of generating gas which consists in blasting through a mass of fuel to maintain the same incandescent and to generate producer gas, in periodically placing green fuel adjacent and in coking proximity to said incandescent mass but temporarily out of the path of the blast, in passing the distillate from said green fuel into
90 the blast and after coking passing the hot blast gases which have previously passed through one portion of said incandescent fuel into and through said intermediate coked green fuel to bring the same to incandescence.
95

4. The process of generating gas which consists in blasting alternately through two bodies of coked fuel to maintain the same incandescent, in placing green fuel adjacent and in coking proximity to one of said bodies of incandescent fuel but out of the path of the blast, in passing the distillate from said green fuel into the adjacent incandescent fuel and in simultaneously passing into said incandescent fuel and commingling with said distillate the hot blast gases from the other mass of incandescent fuel.
100

5. The process of generating gas which consists in alternately blasting air through masses of previously coked fuel to maintain the same incandescent, in placing green fuel adjacent and in coking proximity to one mass to coke the same, in passing the distillate from said green fuel into the adjacent fuel, in simultaneously passing the hot blast gases from the other mass of incandescent fuel into the mass receiving the distillate and after coking passing the hot blast gases through the coked fuel to bring the same to incandescence.
115

6. The process of generating gas which consists in blasting upward alternately through two bodies of coked fuel to maintain the same incandescent, in passing the hot
120

- gases from the body under upward blast downward through the other body, in placing green fuel above the latter body out of the line of the blast, in passing the distillate from said green fuel commingled with the blast gases downward through the adjacent incandescent fuel, and after coking and upon reversal of the blast passing the latter upward through the coked fuel.
- 10 7. The process of generating gas which consists in blasting through a mass of coked fuel alternately from opposite ends and renewing the mass by feeding green fuel

into coking proximity thereto intermediate the blast ends but temporarily out of the path of the blast, in commingling the distillate from said green fuel with the blast gases and after coking passing the blast through the intermediate coked fuel also.

In testimony whereof I affix my signature in presence of two witnesses.
